PICTURE FRAME

Don Wienke, Detroit, Mich.

Application October 29, 1952, Serial No. 22,028

Term of patent 7 years

(Cl. D29—20)

To all whom it may concern:

Be it known that I, Don Wienke, a citizen of the United States, residing in the city of Detroit, in the county of Wayne, in the State of Michigan, have invented a new, original, and ornamental Design for Picture Frames, of which the following is a specification, reference being had to the accompanying drawings, forming part thereof.

Fig. 1 is a perspective view of a picture frame showing my new design.

Fig. 2 is a front elevation of said frame.

Fig. 3 is an end elevation of said frame.

Fig. 4 is a side elevation of said frame.

I claim:

The ornamental design for a picture frame, as shown.

DON WIENKE.
